CLAIM

The ornamental design for a pendant, as shown and described.

DESCRIPTION

FIG. 1 is a top left perspective view of a pendant showing my new design;

FIG. 2 is a top right perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a bottom plan view thereof; and,

FIG. 8 is a top plan view thereof.

The broken lines depict environmental structure that forms no part of the claimed design.
